ATTORNEY

UNITED STATES PATENT OFFICE

126,425

DESIGN FOR A BRACELET OR THE LIKE

James H. Bell, New York, N. Y.

Application February 15, 1941, Serial No. 99,017

Term of patent 3½ years

To all whom it may concern:

Be it known that I, James H. Bell, a citizen of the United States, residing in New York city, county and State of New York, have invented a new, original, and ornamental Design for a Bracelet or the like, of which the following is a specification, reference being had to the accompanying drawing, forming part thereof.

Fig. 1 is a perspective view of a bracelet showing my new design.

Fig. 2 is a top plan view thereof.

Fig. 3 is a rear view thereof.

I claim:

The ornamental design for a bracelet or the like, as shown.

JAMES H. BELL.
